UNITED STATES PATENT OFFICE

2,684,702

MULTIPOCKET WALLET

Arthur S. Silva, Taunton, Mass., assignor to
Swank, Inc., a corporation of Delaware

Application June 30, 1951, Serial No. 234,541

3 Claims. (Cl. 150—38)

1

This invention relates to a wallet which is formed from a plurality of pieces of material to form a plurality of pockets.

One of the objects of this invention is to provide a wallet which will have a minimum amount of stitching or cementing to fasten the parts together.

Another object of the invention is to provide the main portion of the wallet as a structure to which additions may be made to provide a desired number of pockets.

With these and other objects in view, the invention consists of certain novel features of construction as will be more fully described and particularly pointed out in the appended claims.

Figure 1 is a perspective view of a wallet in open position.

Figure 2 is a perspective view showing certain parts folded outwardly so that the structure may be seen.

Figure 3 is a section on line 3—3 of Figure 1.

Figure 4 is a plan view of one of the blanks cut from sheet stock from which the wallet is formed.

Figures 5 and 6 are plan views of additional pieces which are assembled with the piece of Figure 4.

Figure 7 is a fragmental plan view of the wallet taken from between the separator and an inner wall section to show a sliding locking relation of the stay, and one of the wall sections.

With reference to the drawings, the blanks from which the construction is formed are shown in Figures 4, 5, and 6. The blank 10 comprises a main outer wall 11 and a second wall formed of sections 12—12 which are joined to the outer wall 11 along the fold line 13. These sections are spaced at their inner edges as shown at 14, and are also provided with slots 15—15. Tabs 16—16' are joined to the free edge of the sections along the fold lines 17—17. A slit 18 provides a tongue 19 on the tab 16'.

The outer wall 11 may have a tab 20 joined thereto along fold line 21. Third walls 22—22 are joined to the ends of the outer wall 11 along fold lines 23—23, and are provided with dove tailed portions 24—24 having tabs 25 at their outer ends and 26 at their inner ends.

This structure is folded first along the fold line 13, as shown in Figure 2, so as to position the sections 12—12 spaced from the outer wall 11. Then the third walls 22—22 are folded along each fold line 23 over the sections 12 and the dove tail portions 24 are passed through slots 15 with their tabs 25 and 26 extending under the ends of the slots so as to lock the third walls in this position.

2

The stay 28, as cut out in blank in Figure 5, comprises a pair of tabs 29 and 30 which are folded inwardly upon themselves so as to provide a finished edge, and this stay 28 is positioned between sections 12 and the outer wall 11 with its lower edge along the crease or fold 13. This stay spans the space 14 between the sections and is held close to the sections 12 by the tabs 16—16' being folded over the upper edge 31 of the stay 28, the tab 27 extending on the inside of the stay as shown in Figures 1 and 2 so as to present a finished side of the leather between the sections 12 and the lower edge of stay 28.

One end 32 of the stay 28 is secured, such as by stitching, to the section 12 while the other end of the stay is slotted as at 33 to receive through this slot the tongue 19 of the tab 16' (see Figure 7) so that it is slidably related to the other section 12. Thus, as the wall 11 is folded along a line midway of the space 14, this stay may go and come by reason of the slot and tongue connection just mentioned. This stay also provides pockets whose entrance is between the edges 34 of the sections 12, and the pocket end is of the depth of the stay for the reception of cards or the like. Two more pockets which are open at their right angular edges and are entered either through the edge 35 or edge 36 are also formed between the third walls 22 and the sections of the second wall 12.

30 There is also, of course, formed a pocket between the outer wall 11 and the stay for the lengthwise reception of bills. This pocket may be subdivided into two parts for the reception of a bill separator 38, as shown in plan view in Figure 6, and which comprises legs 39 to engage the inner surface of the fold 13. This separator will be of a dimension so that it will stand up slightly above the sections 12, but will be shorter than the outer wall 11. The outer wall may have its tab 20 folded inwardly so as to provide a finished inner surface in that portion which extends above the bill separator 38 and the sections 12.

By this arrangement a large number of pockets may be provided. In the present instance, I have shown four small pockets and two large pockets.

I claim:

1. A wallet comprising an outer wall of generally rectangular shape, a second wall formed in two spaced sections, each of said sections folded from the lengthwise edge of the outer wall and each section having a slot for a portion of its length parallel to the fold and adjacent the fold line, a tab on each of said sections removed from said fold and parallel thereto, third walls each folded from an end of the outer wall over

a slotted section and each having a dove tail portion along one edge only of the wall and extending through a said slot to lock the third walls to the second wall along one edge only thereof, a stay between the outer and second walls spanning the space between the second wall sections and slidably held to a section by the tab thereof being folded over the stay.

2. A wallet comprising an outer wall of generally rectangular shape, a second wall formed in two spaced sections, each of said sections folded from the lengthwise edge of the outer wall and each section having a slot for a portion of its length parallel to the fold and adjacent the fold line, a tab on each of said sections removed from said fold and parallel thereto, third walls each folded from an end of the outer wall over a slotted section and each having a dove tail portion along one edge only of the wall and extending through a said slot to lock the third walls to the second wall along one edge only thereof, a

stay between the outer and second walls spanning the space between the second wall sections and held to the sections by the tab of each of the sections being folded over the stay, one end section having a tongue on its tab, said stay having a slot therein, said stay slidably attached to the end of said one section by said tongue passing through said slot in said stay.

3. A wallet as in claim 1 wherein said stay is secured to the other section.
